CLOTHES HANGER

Maurice E. Dore, Ludington, Mich., assignor to
Straits Steel & Wire Co., Ludington, Mich.

Application October 15, 1951, Serial No. 251,278

7 Claims. (Cl. 211—118)

1

This invention relates to improvements in clothes hangers.

The main objects of this invention are:

First, to provide a clothes hanger which is adapted for use in supporting a plurality of garments for the purpose of storage or for drying, and a hanger which may be compactly collapsed for storage or packing thereof.

Second, to provide a clothes hanger having these advantages which is economical in its parts and may be quickly erected or collapsed, and one in which the rack portion is securely supported in its erected position.

Third, to provide a structure which is formed mainly of wire stock and is easily kept in a sanitary condition.

Objects pertaining to details and economies of the invention will definitely appear from the description to follow. The invention is defined in the claims.

A structure which embodies the features of the invention is clearly illustrated in the accompanying drawing, in which:

Fig. 1 is a front perspective view of a hanger embodying my invention in erected position.

Fig. 2 is a front view with the rack in collapsed position, the suspending hook being partially broken away.

Fig. 3 is an edge view with the rack in collapsed position, the suspending hook being shown partially broken away in full lines and collapsed by dotted lines.

Fig. 4 is an enlarged fragmentary view partially in section on a line corresponding to line 4—4 of Fig. 2 showing details of the mounting of the suspending hook.

Fig. 5 is a fragmentary view in section on a line corresponding to line 5—5 of Fig. 2 showing structural details.

Fig. 6 is an enlarged fragmentary view in section on a line corresponding to line 6—6 of Fig. 1 illustrating the fulcruming engagement of the rack supporting struts with the frame.

The embodiment of the invention illustrated comprises a frame designated generally by the numeral 1 and comprising a bottom member 2, side members or uprights 3, 3 and a top member 4. These members are preferably formed integrally of wire. The top member is of a flattened inverted V or yoke shape. A cross bar 5 of springable wire stock is secured to the side members of the frame in spaced relation to their upper ends. This cross bar is provided with a forwardly projecting loop intermediate the ends constituting a keeper 6. The arms 6' of the loop

2

have notches 7 therein adapted to receive the rack bar 8 when the rack is collapsed.

The rack comprises side members 9 terminating in eyes 10 at their inner ends which are pivotally engaged with the bottom frame member 2 at the inner sides of the side members 1. The rack also includes a plurality of rack bars 11 disposed in spaced parallel relation with their outer ends upon and welded to the rack side members. 10 The outer rack bar 9 in this embodiment is formed integrally with the side members.

The rack is collapsible against the front of the frame as illustrated in Fig. 2 and when collapsed the rack bar 8 is springably engageable with the keeper 6, holding the rack in its collapsed position.

The rack is supported in its erected position by the wire struts 12 which have angularly disposed eyes 13 at the upper ends thereof. These eyes 20 pivotally engage the side members of the frame above the cross member 5 thereof. The struts 12 are formed of springable stock, desirably wire, and terminate at their lower ends in rearwardly disposed upwardly facing hooks 14. The struts 25 slidably engage one of the rack bars and during the latter portion of the erecting swing of the rack the struts are placed under spring stress owing to the upper ends of the struts being in fulcruming engagement with the cross bar 5 of the frame, as is best shown in Fig. 6. This biasing or spring stress of the struts results in the automatic engagement of the hooks with the rack bar which they are slidably associated.

To permit compact collapsing of the struts against the collapsed rack, the struts are provided with portions 15 offset in relation to the strut which allow them to collapse into substantially parallel relation to the side members of the rack and against the outer side thereof when the rack 40 is in collapsed position.

The frame is provided with a suspending hook 16, the shank 17 of which is provided with a clip-like attaching member 18 formed of a generally U-shaped sheet metal stamping. The bight 19 of the stamping has a hole 19' therein receiving the shank of the hook which is provided with a retaining collar 20. The arms 21 of the member 18 springably engage the top member 4 at the apex thereof and, owing to their converging relation, they frictionally urge the end of the shank against the frame top member. This engagement permits the hook being swung to erected position as shown in Figs. 1 and 4, or to collapsed position as shown in Fig. 3 by dotted lines.

The friction is such that the hook is held in its erected position or in its collapsed position.

Garments may be draped over the rack bars or they may be secured thereto by means of clothes pins conventionally shown at 22. These pins are desirably of the spring type and of plastic material. Such clothes pins are commercially available. When the rack is collapsed it may be used for supporting a plurality of garments such as trousers which may be draped over the rack bars.

I have illustrated and described the invention in a commercial embodiment which I regard as highly practical. I have not attempted to illustrate or describe other modifications and adaptations as it is believed this disclosure will enable those skilled in the art to embody or adapt the invention as may be desired.

Having thus described the invention what is claimed as new and desired to secure by Letters Patent is:

1. In the clothes hanger the combination of a frame comprising bottom, side and top members of wire, the top member being of yoke shape, a springable crossbar connected to the side members of the frame adjacent the upper end of each side member of the frame and having a central forwardly projecting loop therein constituting a keeper, a rack formed of wire comprising side members and a plurality of spaced parallel rack bars, the front rack bar being formed integrally with the side members, the side members terminating at their inner ends in eyes pivotally embracing the bottom frame member at the inner sides of the frame side members, struts disposed at their upper ends on the inner sides of the side members and having angularly disposed forwardly projecting eyes embracing the side members above said frame crossbar and disposed between adjacent rack bars and slidably engaging one of the rack bars, said struts having rearwardly and upwardly facing rack bar engaging hooks at their lower ends, the eyes at the upper ends of the struts being in fulcruming engagement with the frame cross bar during the latter portion of the erecting swing of the rack to springably urge the struts against the rack bar with which they are slidably engaged, one of the rack bars being positioned for springable engagement with the said keeper when the rack is collapsed, the struts, each having a portion forwardly offset in relation to the strut adjacent its upper end so that their outer portions are collapsible upon the forward side of the collapsed rack and between the side members thereof and a collapsible hook pivotally and frictionally mounted on the frame top member at the apex thereof.

2. In the clothes hanger the combination of a frame comprising bottom, side and top members of wire, a springable crossbar connected to the side members of the frame adjacent the upper end of each side member of the frame and having a central forwardly projecting loop therein constituting a keeper, a rack formed of wire comprising side members and a plurality of spaced parallel rack bars, the side members terminating at their inner ends in eyes pivotally embracing the bottom frame member at the inner sides of the frame side members, struts disposed at their upper ends on the inner sides of the side members and having angularly disposed forwardly projecting eyes embracing the side members above said frame crossbar and disposed between adjacent rack bars and slidably engaging one of the rack bars, said struts having rearwardly and

upwardly facing rack bar engaging hooks at their lower ends, the eyes at the upper ends of the struts being in fulcruming engagement with the frame crossbar during the latter portion of the erecting swing of the rack to springably urge the struts against the rack bar with which they are slidably engaged, one of the rack bars being positioned for springable engagement with the said keeper when the rack is collapsed.

3. In the clothes hanger the combination of a frame comprising bottom, side and top members, a springable crossbar connected to the side members of the frame adjacent the upper end of each side member of the frame and having a forwardly projecting keeper, a rack comprising side members and a plurality of spaced parallel rack bars, the side members being pivotally mounted at their inner ends on the bottom frame member, struts of springable stock disposed with their upper ends on the inner sides of the side members and at the rear of the frame crossbar and having angularly disposed forwardly projecting eyes embracing the side members above said frame cross bar, said struts being associated with one of the rack bars, said struts having rearwardly disposed upwardly facing rack bar engaging hooks at their lower ends, the struts being in fulcruming engagement with the frame cross bar during the latter portion of the movement of the rack to erected position to springably engage the rack bar with which they are slidably associated, one of the rack bars being positioned for springable engagement with the said keeper when the rack is collapsed.

4. In the clothes hanger the combination of a frame comprising bottom, side and top members, a crossbar connected to the side members of the frame adjacent the upper end of each side member of the frame, a rack comprising side members and a plurality of spaced parallel rack bars, the side members being pivotally mounted at their inner ends on the bottom frame member, struts of springable stock disposed with their upper ends on the inner sides of the side members and at the rear of the frame crossbar and having angularly disposed forwardly projecting eyes embracing the side members above said frame crossbar, said struts being slidably associated with one of the rack bars, said struts having rearwardly disposed upwardly facing rack bar engaging hooks at their lower ends, the struts being in fulcruming engagement with the frame crossbar during the latter portion of the movement of the rack to erected position to springably engage the rack bar with which they are slidably associated.

5. In the clothes hanger the combination of a frame comprising bottom, side and top members, a crossbar connected to the side members of the frame adjacent the upper end of each side member of the frame, a rack comprising side members and a plurality of spaced parallel rack bars, the side members being pivotally mounted at their inner ends of the bottom frame member, struts of springable stock disposed with their upper ends on the inner sides of the side members and at the rear of the frame crossbar and having angularly disposed forwardly projecting eyes embracing the side members above said frame crossbar, said struts being slidably associated with one of the rack bars, said struts having rearwardly disposed upwardly facing rack bar engaging hooks at their lower ends, the struts being in fulcruming engagement with the frame crossbar during the latter portion of

the movement of the rack to erected position to springably engage the rack bar with which they are slidably associated, the struts having forward offsets in relation to the struts adjacent their upper ends so that their outer portions are collapsible upon the forward side of the collapsed rack between the side members thereof and a collapsible hook having pivotal frictional mounting on the frame top member with the apex thereof.

6. In the clothes hanger the combination of a frame comprising bottom, side and top members of wire, a crossbar connected to the side members of the frame adjacent the upper end of each side member of the frame, a rack formed of wire comprising side members and a plurality of spaced parallel rack bars, the side members terminating at their inner ends in eyes pivotally embracing the bottom frame member at the inner sides of the frame side members, and struts of springable stock disposed at their upper ends on the inner sides of the side members and having angularly disposed forwardly projecting eyes embracing the side members above said frame above said crossbar and slidably engaging one of the rack bars, said struts having rack bar engaging hooks at their lower ends, the struts being in fulcruming engagement with the frame crossbar during the latter portion of the erecting swing of the rack to springably urge the struts

against the rack bar with which they are slidably engaged.

7. In the clothes hanger the combination of a frame comprising bottom, side and top members, a crossbar connected to the side members of the frame adjacent the upper end of each side member of the frame, a rack comprising side members and a plurality of spaced parallel rack bars, the side members pivotally mounted on the bottom frame member and struts of springable stock having eyes embracing the side members above said frame above said crossbar and slidably engaging one of the rack bars, said struts having rack bar engaging hooks at their lower ends, the struts being in fulcruming engagement with the frame crossbar during the latter portion of the erecting swing of the rack to springably urge the struts against the rack bar with which they are slidably engaged.
